UNITED STATES PATENT OFFICE.

LEWIS H. MORRILL, OF HARVEY, ILLINOIS, ASSIGNOR TO THE BUDA COMPANY, OF HARVEY, ILLINOIS, A CORPORATION OF ILLINOIS.

TURBINE CONSTRUCTION.

Application filed March 3, 1927. Serial No. 172,292.

This invention relates to turbine constructions in general and more particularly to such constructions as employ return blades mounted adjacent the turbine wheel blades for further utilizing the velocity of the steam on the latter blades, and aims to provide such a construction as will permit a maximum of accessibility to said return blades for inspection, renewal, repair, or assembly thereof.

Return blades of the above type require considerable attention, and in the turbine constructions which have been in general use heretofore, it has usually been necessary to remove a comparatively large portion of the turbine casing in order to obtain access to such blades.

It is accordingly an object of this invention to provide a turbine construction wherein only a comparatively small part of the turbine casing need be removed to obtain access to the return blades of the turbine. More specifically, it is an object of this invention to provide a turbine construction in which the return blades of the turbine are so mounted that they may be removed with a maximum of convenience from a comparatively small opening.

Further and more specifically, it is an object of this invention to provide a turbine construction in which a small opening and removable closure therefor is provided adjacent the return blades through which opening access to the said blades may be attained.

Still more specifically, it is an object of this invention to provide in connection with the said opening, a mounting for said return blades embracing outwardly removable retaining means accessible through said opening for facilitating assembly or removal of said blades through said opening.

Other and further objects of this invention will be apparent as the same becomes better understood from an examination of the specification and claims in connection with the accompanying drawings illustrating a preferred embodiment, in which,

Fig. 1 is a longitudinal fragmentary elevational view of the exterior of a turbine housing forming a part of a turbine generator set,

Fig. 2 is a fragmentary sectional view taken on the line 2-2 of Fig. 1 and having

parts removed to show the character of the 55 mounting for the return blades,

Fig. 3 is an enlarged fragmentary view taken at the line 3-3 of Fig. 2,

Fig. 4 is an enlarged fragmentary sectional view taken at the line 4-4 of Fig. 2, and 60

Fig. 5 is an enlarged fragmentary view taken at the line 5-5 of Fig. 2.

Referring to the drawings more particularly, numeral 1 indicates generally the housing of the turbine which, in this instance, forms a part of a turbine generator set, the generator housing (not shown) joining the said housing 1 at the right, as viewed in Fig. 1. The housing 1 is constructed of aligned cylindrical sections 2 and 3 which 65 are joined together and an end or cover section 4 which closes the end of the section 3 opposite said section 2. The latter section 2 is cast with a wall 5 closing the end opposite the section 3. A turbine wheel 6 70 and shaft therefor 7 is mounted within the housing 1 in any suitable manner.

The turbine wheel 6, according to this illustration, is provided at the side thereof and along its outer periphery with circumferentially arranged buckets or blades 8, said buckets extending axially from the side of said wheel and being reinforced by suitable rings 9 connected to the ends of the buckets. Each of the buckets 8 is provided 85 with a stem 10 which extends through the wheel 6 and is upset at the side of said wheel opposite to the bucket to retain the latter. The wheel 6, in order that the buckets or 90 blades 8 may be sufficiently spaced therefrom to permit the return buckets to extend beneath said buckets 8, is provided with an annular shoulder 11 at its peripheral edge on which said buckets 8 are mounted.

The wall 5 of the section 2 is provided on 95 its inner side with an arcuate ledge 12 which is provided as viewed in Fig. 5 with peripherally spaced lugs 13 on which is mounted a removable mount 14 of the return buckets or blades 15. The mount 14 is provided 100 at its lower edge with an arcuate flange having a pair of peripherally spaced retaining members in the form of screws 16 therein, each of which is threaded in a radial direction in one of the lugs 13 respectively.

The screws 16 may be provided with elongated heads (not shown) to facilitate operation and are operable by means of a tool

which may be inserted radially with respect to the housing 1 through an opening 17 in the periphery of the section 2 opposite the mount 14. The opening 17 need be no larger than that necessary to receive the mount 14 therethrough.

Steam is directed to the buckets 15 by a nozzle 18 mounted at a suitable angle in the section 2 at one side of said opening 17. A 10 suitable control valve 19 communicating at one side thereof with a passage 20 which in turn communicates with a source of steam supply 21 is adapted to deliver steam through a passage 22, communicating with 15 the other side of said valve, to said nozzle.

The opening 17 is provided with a closure plate 23 which in this instance is shaped to provide a threaded opening therein forming an exhaust outlet 24. The plate 23 is mounted upon a suitable shoulder 25 and is held on said shoulder by bolts 26.

It will be obvious that by reason of the removable mount 14 which may be removed through the opening 17 after the closure plate 23 has been removed, access to the turbine blades is greatly facilitated.

I am aware that many changes may be made without departing from the principles of this invention, and I do not wish to be limited to the details shown and described.

I claim:

1. In a turbine construction, a casing, a turbine wheel mounted therein, said casing having an opening and closure therefor adjacent the periphery of said wheel, and return buckets and mounting therefor within said casing, said mounting including means accessible through said opening for permitting the removal of said buckets.

40 2. In a turbine construction, a casing, a turbine wheel mounted therein, said casing having an opening and closure therefor adjacent the periphery of said wheel and return buckets mounted therefor within said casing, said mounting including radially movable means accessible through said opening for permitting the removal of said buckets.

3. In a turbine construction, a sectional casing, a turbine wheel mounted therein, said casing having an opening in one of the sections thereof and a closure plate for said opening, said opening being adjacent the periphery of said wheel, return buckets mounted within said casing, and a mounting therefor including means accessible through said opening for permitting the removal of said buckets.

4. In a turbine construction, a sectional casing, a turbine wheel mounted therein, said casing having an opening in one of the sections thereof and a closure plate for said opening, said opening being opposite the periphery of said wheel, return buckets mounted within said casing, and a mount-

ing therefor including radially movable means accessible through said opening for permitting the removal of said buckets.

5. In a turbine construction, a casing, a turbine wheel mounted therein, said wheel having axially extending buckets circumferentially arranged thereon, said casing having an opening and closure therefor adjacent the periphery of said wheel, and return buckets and mounting therefor within said casing, the return buckets being arranged adjacent the inner periphery of the turbine wheel buckets, the mounting for said return buckets including means accessible through said opening for permitting the removal of said return buckets.

6. In a turbine construction, a casing, a turbine wheel mounted therein, said wheel having axially extending buckets circumferentially arranged thereon, said casing having an opening and closure therefor adjacent the periphery of said wheel, and return buckets removably mounted within said casing and arranged adjacent the inner periphery of the wheel buckets, the mount for said return buckets having radially operable retaining means accessible through said opening.

7. In a turbine construction, a casing, a turbine wheel mounted therein and having buckets thereon, said casing having an opening and closure therefor adjacent the periphery of said wheel, return buckets and mounting therefor within said casing, said mounting including means accessible through said opening for permitting the removal of said return buckets, and a nozzle mounted in said casing at one side of said opening and adapted to direct steam to said first buckets.

8. In a turbine construction, a casing, a turbine wheel mounted therein having buckets thereon, said casing having an opening and closure therefor adjacent the periphery of said wheel, return buckets and mounting therefor within said casing, said mounting including radially movable means accessible through said opening for permitting the removal of said return buckets, and a nozzle mounted in said casing at one side of said opening and adapted to direct steam to said first buckets.

9. In a turbine construction, a casing, a turbine wheel mounted therein, said casing having an opening and closure therefor adjacent the periphery of said wheel, said opening being adapted to expose a relatively small part of said periphery, and return blades and mounting therefor within said casing, said mounting including means accessible through said opening for permitting the removal of said blades.

10. In a turbine construction, a casing, a turbine wheel mounted therein, said casing having an opening and closure therefor ad-

11 jacent the periphery of said wheel, said opening being adapted to expose a relatively small part of said periphery, and return blades and mounting therefor within said 5 casing, said mounting including radially movable means accessible through said opening for permitting the removal of said blades.

11. A turbine construction comprising a 10 rotatable turbine wheel provided with pe-

ripheral buckets, removable return buckets adjacent said wheel buckets, a casing surrounding said wheel and provided radially of the wheel with an opening through which 15 access to said wheel and return buckets may be obtained, and a removable closure for said opening.

In witness of the foregoing, I affix my signature.

LEWIS H. MORRILL.
